(57) **CLAIM**

The ornamental design for a portable infrared camera, as shown and described.

DESCRIPTION

FIG. 1 is a front perspective view of a portable infrared camera, showing our new design;
 FIG. 2 is front view thereof;
 FIG. 3 is a back view thereof;
 FIG. 4 is a bottom view thereof;
 FIG. 5 is a first side view thereof;
 FIG. 6 is a second side view thereof; and,
 FIG. 7 is a top view thereof.

The broken lines depict portions of the portable infrared camera in which the design is embodied that form no part of the claimed design.

The dot-dash lines in FIG. 7 denote the boundary of the claim and form no part of the claimed design.
